LATCH FOR SAFETY HOOKS

Richard K. Hertel, Vernon, Calif., assignor to
Byron Jackson Co., Huntington Park, Calif.,
a corporation of Delaware

Application May 6, 1936, Serial No. 78,185

5 Claims. (Cl. 294—83)

This invention relates to rotary and casing hooks such as are employed for raising and lowering drill pipe or casing in an oil well. More particularly, the invention relates to improvements in locking devices for latch links in hooks of the type shown in U. S. Patent No. 1,825,018 issued Sept. 29, 1931, to Nelson K. Smith.

In the hook illustrated in Patent No. 1,825,018, there is a hook member 17 having a body 43, with a forwardly extending bill forming a bail-receiving notch 41 and a latch link arm 44 pivoted to the end of the bill and adapted to engage a protrusion 50 formed on the body 43 above the notch 41 so that a part of the load on the hook will be carried by the latch link arm 44 and the protrusion 50. The latch link arm 44 is provided with a safety locking device comprising a sliding latch bolt 57 yieldably supported on a coil compression spring 62. The movement of the latch bolt 57 is in substantially a vertical plane parallel to the vertical axis of the hook. With a lock of the type described above, there is the possibility, under certain conditions, of accidentally releasing the latch link arm 44. For example, if the hoisting line should break, the resulting jar on the hook would be in substantially a vertical plane and might cause the heavy latch bolt 57 to compress the spring 62 and release the latch link arm.

It is the object of the present invention to provide an auxiliary locking device for the latch bolt 57 so that a jar in any given direction can not accidentally release the latch link arm 44.

Figure 1 is a side elevation, partly in cross section, of a hook embodying my improved latch lock.

Figure 2 is a fragmentary vertical cross section taken through the latch of Fig. 1 showing the latch in the locked position.

Figure 3 is similar to Fig. 2, but showing the latch in the released position.

Figure 4 is a fragmentary front elevation, partly in cross section, of the latch shown in Fig. 2.

Although the only part of the hook which constitutes the present invention is the latch link lock, I will for convenience describe a complete hook embodying my invention.

The complete hook consists of a yoke 1, supporting a pair of bails 2 which support a trunnion 3. The hook shank 4 extends slidably through the trunnion 3 and is supported upon a coil compression spring 5, which is supported within the housing 6. Housing 6 is supported on an anti-friction bearing 7 carried by the trunnion 3. The hook body is indicated at 9 and is supported from the

lower end of shank 4 by a cross pin 11. In the present instance the hook body is provided with a pair of oppositely disposed elevator link supporting arms, one of which is shown at 13. These arms are at a right angle to the bill of the hook and are provided with links 15 which close the entrance to the arms 13. Each link 15 is provided with locking means 17 and 19. The hook body 9 has a forwardly extending bill 21 forming a bail-receiving notch 23. Pivoted to the end of the bill 21 is a latch link arm 25. The pivot pin is shown at 27. The upper end of arm 25 is provided with a head 29 adapted to engage a protrusion 30 formed on the body 9. The arm 25 is formed with a channel portion 32 adapted to receive latch bolt and latch lock. The arm 25 is provided at its lower end with an inwardly extending finger 26 adapted to be engaged by a bail 28 inserted in notch 23 to automatically close the latch link arm 25.

The latch comprises a latch bolt 34 supported upon a substantially vertical coil compression spring 36, and an auxiliary latch lock 38 pivotally mounted on the latch bolt 34 as indicated at 40. The latch bolt 34 is provided at its upper end with nose 35 having a cam surface 37 adapted to engage the lower cam face 31 of the protrusion 30. The protrusion 30 is provided with a recess 33 adapted to receive the latch nose 35 and forming a forward wall 39 adapted to restrain the latch nose against opening movement. The lower end of the latch bolt 34 is provided with a depending skirt 41 adapted to receive the upper end of spring 36. The skirt 41 is received slidably in a recess 42 formed in the latch arm 25. The spring 36 is supported in the recess 42. The upper end of latch bolt 34 is guided by a roller 44 mounted on a pin 46 secured in the latch arm 25 and working in a slot 47 formed in the latch bolt 34. The latch bolt 34 is provided with a forwardly extending notch 48. A downward pull on the notch 48 will compress the spring 36 and permit the latch link arm 25 to be disengaged from the protrusion 30.

The latch and lock construction described above is substantially the same as that shown in Patent No. 1,825,018, but is described here because the latch lock 38, which is the improved feature of the hook, co-operates with the latch bolt 34 to prevent accidental opening of same.

The latch lock 38 comprises a lever pivoted intermediate its ends to the latch bolt as indicated at 40. The lever 38 is received in a slot 50 formed in latch bolt 34. The lower end 51 of lever 38 protrudes from the latch bolt 34 in front of

the skirt 41 and is adapted to rest upon a shoulder 52 formed on the latch arm 25. A horizontal coil compression spring 54 is mounted in a recess 56 formed in latch bolt 34 and is adapted to press 5 the lower end 51 of lever 38 outwardly so that it will normally engage the shoulder 52 and prevent the latch from being opened accidentally. In order to open the latch the lever 38 is provided with a forwardly extending finger 58 which ex- 10 tends into notch 48 and extends slightly above the bottom of the notch, so that a downward pull in notch 48 first swings lever 38 about its pivot 40 and moves the lower portion 51 off of shoulder 52, toward the skirt 41. A further downward pull 15 on notch 48 will compress spring 36 and permit the latch to be released. The lever portion 51 is restrained against forward movement such as would move it off shoulder 52, by the depending guard portion 63 of latch bolt 34.

20 Since a hook of the type described above is automatically closed and locked by means of a bail engaging the finger 26 in notch 23 it is necessary to provide means other than the finger 58 for moving the lever 38 off of shoulder 52. I 25 accomplish this result by extending the upper lever arm 62 beyond the cam surface 37 of latch bolt 34 a short distance. Thus when the latch link arm 25 is in the open position the locking parts will be in the same position as when the 30 hook is closed as shown in Fig. 2. When the closing movement of arm 25 causes the upper end of lever arm 62 to engage the cam surface 37 on protrusion 30 the lever 38 will be swung on its pivot 40 so that the lower end 51 of the lever 38 is moved off of shoulder 52. Further closing movement of the latch arm 25 is then possible and results in the latch bolt 34 being pushed down against spring 36 and permitting full closing. When the nose 35 passes the wall 39, spring 40 36 snaps the latch bolt 34 upwardly into locked position and spring 54 pushes lever arm 51 over the shoulder 52, thus doubly locking the latch arm 25 in the closed position.

It will be noted that the forces required for 45 moving the two latches are exerted along lines at substantially a right angle to each other. In the present instance this is accomplished by positioning the axes of the latch springs 36 and 54 at substantially a right angle to each other, 50 with one spring being in substantially a horizontal position. This is to insure that a shock or jar in any given direction will not unlock the latch arm 25, since only one of the locks will be affected by any given jar.

55 While I have shown my invention in conjunction with a hook having a closing finger 26 adapted to be engaged by a bail inserted in notch 23 to automatically close the latch arm 25, it is to be understood that my invention can be used 60 with hooks which do not have this automatic closing feature. It is also to be understood that my invention can be used on hooks which have a latch arm pivoted to the bill to close the entrance to the bail-receiving notch whether or 65 not the latch arm engages a protrusion on the hook body so as to carry a part of the load.

I claim:

1. In a safety hook having a body with a forwardly extending bill forming a bail-receiving 70 notch, and a latch arm pivoted to said bill and

adapted to close the entrance to said notch, a latch bolt slidably mounted on said latch arm and having its upper end adapted to engage the hook body in camming relation thereto to retract said bolt upon closing movement of said latch arm, a spring yieldably supporting said latch bolt, a latch lock comprising a lever pivotally mounted on said latch bolt and having upper and lower lever arms, said upper lever arm protruding slightly beyond the upper end of said latch bolt and being adapted to engage the hook body in camming relation thereto in advance of said latch bolt, said lower lever arm being adapted to be shiftably supported upon a shoulder on said latch arm, a spring normally urging said lower lever arm into shoulder engaging relation, and manual means for moving said latch bolt and lever to the unlocked position.

2. In a safety hook having a body with a forwardly extending bill forming a bail-receiving notch, and a latch arm pivoted to said bill and adapted to close the entrance to said notch, a latch bolt slidably mounted on said latch arm for movement in a substantially vertical plane and having its upper end adapted to engage the hook body in camming relation thereto to retract said bolt upon closing movement of said latch arm, a coil compression spring yieldably supporting said latch bolt and having its axis in a substantially vertical plane, a latch lock comprising a lever pivotally mounted on said latch bolt and having upper and lower lever arms extending in a substantially vertical plane, said upper lever arm protruding slightly beyond the upper end of said latch bolt and being adapted to engage the hook body in camming relation thereto in advance of said latch bolt, said lower lever arm being adapted to be shiftably supported on a shoulder on said latch arm, spring means normally urging said lower lever arm laterally into shoulder engaging relation and manual means for simultaneously moving said latch bolt and lever to the unlocked position.

3. In a safety hook having a body with a forwardly extending bill forming a bail-receiving notch and a latch arm pivoted to said bill and adapted to close the entrance to said notch, a latch bolt slidably mounted on said latch arm for movement in a substantially vertical plane, spring means normally urging said latch bolt toward the locked position, a latch lock pivotally mounted on said latch bolt, spring means normally urging said latch lock toward the locked position, and adapted to be actuated by a force applied in a substantially horizontal direction, and manual means for simultaneously moving said latch bolt and latch lock to the unlocked position.

4. A safety hook as defined in claim 3 in which the pivoted latch arm is provided with an inwardly extending finger adapted to extend into said notch and to be engaged by a bail received in said notch to automatically close said latch arm.

5. A safety hook as defined in claim 3 in which the pivoted latch lever arm is provided with a shoulder at its free end adapted to engage a protrusion formed on the hook body adapted to carry a part of the load on the hook.

RICHARD K. HERTEL. 70
